DESIGN FOR A TOY FIGURE

Henry M. Kass, Seattle, Wash.

Application November 19, 1945, Serial No. 123,896

Term of patent 7 years

(Cl. D34—4)

To all whom it may concern:

Be it known that Henry M. Kass, a citizen of the United States, residing at Seattle, Washington, has invented a new, original, and ornamental Design for a Toy Figure, of which the following is a specification, reference being had to the accompanying drawing, forming a part thereof, in which:

Fig. 1 is a view in front elevation of a toy figure showing my new design; and

Fig. 2 is a view in side elevation of the toy figure of Fig. 1.

I claim:

The ornamental design for a toy figure, substantially as shown.

HENRY M. KASS.
